ELIJAH C. ORR, OF SEATTLE, WASHINGTON, ASSIGNOR TO ORR SAW TOOTH GRINDER CO., OF SEATTLE, WASHINGTON, A CORPORATION OF WASHINGTON

INSERTED-TOOTH SAW

Application filed June 27, 1927. Serial No. 201,629.

My invention relates to inserted teeth saws, and consists of certain improvements in construction whereby two teeth may be inserted in one recess in the saw center, and whereby also the two teeth of a pair may be made of different types or different construction, thus cooperating to produce a more perfect and smooth cut.

The object of my invention is to so improve such saws as both to increase their capacity and to improve the quality of work done.

My invention is more particularly designed for application to cross-cut saws, by this meaning saws which are intended particularly for cutting transversely of the fibers or grain of the wood.

My invention consists in the improvements of construction of which typical samples are shown in the drawings and described in the following specification.

Figure 1 shows a section of a saw center made in accordance with my invention, a few of my improved teeth being shown in place.

Figure 2 shows a pair of teeth mounted in a fragment of a saw center.

Figures 3 and 4 illustrate, respectively, the raker tooth 2 and the scoring teeth 3 by sections taken, respectively, on the lines 3—3 and 4—4 of Figure 2.

Figures 5 and 7 are face views similar to Figure 2, showing other shapes of teeth.

Figures 6 and 8 are sections taken, respectively, on lines 6—6 and 8—8 of Figures 5 and 7.

Figure 9 is an end view of the tooth 3 shown in Figures 7 and 8.

One characteristic of my invention is the placing of two teeth in one recess in the saw center or disk, both being held in place by the same locking piece.

Another characteristic which may not in all cases be used, consists in making the teeth of each pair of different type, each adapted to perform different functions and cooperating to secure a more perfect result.

A saw having teeth as illustrated in the accompanying drawings, has been designed for the particular purpose of serving as a cut-off saw, or in cutting up material, such

for instance as ply-wood, where at least part of the wood has its fibers cut crosswise. The purpose of the particular shape of teeth shown has been to provide a saw which will make a clean and smooth cut in such materials.

In the drawings, 1 indicates the center or main body portion of a circular saw having recesses 10 in its periphery for the reception of inserted teeth. The edge surfaces of contacting parts of the saw center and the teeth parts are supposed to be of complementary ridge and channel shapes, as is standard practice in inserted tooth saws. Specific description of this feature is not deemed necessary, as the same is well understood in the art and any type of interlocking edge shape found sufficient may be employed.

The outline of the teeth-receiving recesses 10 employed is circular arcuate, the arc being greater than 180 degrees in extent. The edge sections 11 of the saw center between the teeth-receiving recesses 10 are preferably given the same interlocking rib and groove construction, and have, in the saw illustrated, been given an arcuate contour, outwardly convex. The arcuate shape at this point I consider convenient but not essential.

The two types of teeth 2 and 3 employed in each pair are alike in the means employed in securing them in place. Each has an arcuate shank 20 and 30, respectively, on its outer or convex edge made complementary to the edge walls of the receiving recess 10. The end faces of these shanks contact, or approximate to contact, at or about on the middle of the extent of the recess wall, as indicated at 24.

The shank of each tooth and the recess wall are provided with interlocking projections and recesses, as indicated at 21, by which means arcuate sliding movement between the two is prevented. It is preferred that these interlocking members be located at different points for the respective teeth, so that they must be properly positioned when inserted.

The teeth-locking and holding members 4 are disks having interlocking peripheral edges, and being of circular outline cut away at one side to permit of insertion, and also

to conform to the outline of the chip-receiving throat between the teeth. This locking disk is preferably slotted so as to provide some resiliency and to make it possible to tighten it in case it fits loosely. I have shown two holes 40, which may serve to receive a spanner whereby to turn it, these being joined to a central hole 43 by slots 41 and the central hole connected with the edge by a slot 42. These details are however not strictly essential.

After insertion, or if the fit be loose, a rivet placed in the central hole 43 and hammered down, will expand and produce a tight fit. It will also serve as a supporting or stiffening connection between opposite arms of the disk 4 to bear the thrust of the leading tooth 3.

The direction of revolution of the saw is indicated by the arrow 9 in Figures 1, 2 and 7. The leading tooth 3 is of the type called a cutting tooth; that is, it is designed to cut the fibers at the edge of the kerf, while the following tooth 2 is a raker tooth, or one designed to act as a chisel to remove the chip. It is, of course, evident that both teeth might be made exactly alike as to their cutting form and edges, if this fitted the service desired, but for the purpose hereinbefore specifically mentioned, the differences of construction herein mentioned are desirable.

For this specific service the teeth 3 are given a cutting edge 35 at each side, and this edge is inclined relative to the path of movement, the advancing corner 34 being lower than the following corner 33. In consequence, this tooth makes a draw cut and will, as a result, cut more smoothly than would another type of tooth in which the leading corner was the higher.

The tooth 3 illustrated in Figures 2 and 4 has a smooth, uninterrupted edge. The tooth shown in Figures 7, 8 and 9 is the same except that it has channels 36 in the outer side faces of its wings, thus providing cutting edges acting as the bit of a plane to smooth up the side walls of the kerf.

The tooth 3 illustrated in Figures 5 and 6, is divided into two chisel ends 37, one following after the other, and each cutting or scoring its side of the kerf. As a result of using the side scoring or cutting teeth 3 and the raker teeth 2, cleaner cutting is secured, especially in material which is difficult to cut smoothly.

If the raker teeth 2 be positioned so that their cutting edges are the least bit nearer the saw center than the outermost tips of the cutter teeth 3, an exceptionally smooth cut will be produced. This result is also contributed to by the formation of planing edges by the grooves 36 on the side faces of the teeth 3.

By my present invention in which two teeth are secured in one recess, I am able to mount more teeth upon a saw of given size,

which in itself contributes to more rapid and smooth cutting at a given speed.

By using teeth of two types, namely cutters and rakers, I am able to produce results in smoothness of cut directly by the saw, not obtainable by any saw known to me and fairly comparable with results heretofore produced only by using a special finishing step after cutting with a saw. To secure greatest smoothness of cut I prefer that the acting edges of the cutter teeth 3 extend outwardly a sufficient distance from the center of the saw that the cutting edges of the cutter teeth first sever the fibers at the edges of the kerf and the raker teeth then remove a thin shaving.

A saw of the type contemplated may be used for cutting thin stock, as ply wood, in which case the ability to use a high rate of feed is highly desirable. If the side cutting teeth of complementary pairs are placed very far ahead of the raker tooth which removes the wood cut across by the side cutting teeth, a high rate of feed causes rough cutting.

The ideal relative position for the two complementary teeth of any pair, is a projection of the side cutting tooth beyond the raker tooth an amount equivalent to the feed of the material during the time required for the saw to turn through the arc which separates the tips of the two teeth. Referring to the drawings, this arc would be the distance between the adjacent tips of teeth 2 and 3 of a pair. When this condition obtains, the side cutting teeth cut as deep as the rakers and no fibers are torn across at the sides of the kerf.

If the teeth of a saw are positioned to secure this result for a given rate of feed, a higher rate of feed causes tearing across of the fibers for a depth corresponding with the amount of increased feed. It is evident that if the raker tooth follows closely behind its side cutting tooth, this depth of tearing will be much less than if it follows at a much greater angular distance. It is therefore highly important, in order to adapt a saw to widely differing rates of feed, that each raker tooth follow as closely as feasible behind its cutter tooth.

To secure this close spacing with an inserted tooth saw it is necessary that both teeth of a pair be placed in a common recess in the saw body. It is also desirable that their outermost cutting tips be extended towards each other. By this expedient I get the two cutting tips close together and by projecting the cutting teeth but little more than is necessary for a slow feed, they are projected enough for a high feed and the saw will cut smoothly for all practicable rates of feed.

What I claim as my invention is:

1. A circular saw having tooth receiving recesses, complementary teeth for each recess and teeth locking means, the tooth which is positioned ahead of its mate having peripheral cutting edges on the plane of its side

faces and inclined slightly to the path of movement to thereby produce a draw cut, the following tooth of the pair being a raker tooth positioned to act close behind its companion and projected in a radial direction to cut to approximately the same depth as the side cutting tooth.

2. A circular saw having tooth receiving recesses, complemental teeth for each recess, and a common securing means for the teeth of each pair, the leading tooth of each pair having cutting edges, acting to cut the fibers at the side margins of the kerf and the following tooth of each pair being a chisel pointed tooth adapted to remove the chip which has been cut across by the leading tooth and having its cutting point positioned close behind the leading tooth.

Signed at Seattle, King County, Washington, this 3rd day of June 1927.

ELIJAH C. ORR.
